CIRCUIT BREAKER HOLDING MAGNET AND
ARMATURE

Donald I. Bohn, Pittsburgh, Pa., assignor to
I. T. E. Circuit Breaker Company, Philadelphia,
Pa., a corporation of Pennsylvania

Application July 28, 1942, Serial No. 452,613

7 Claims. (Cl. 175—336)

1

My invention relates to circuit breaker apparatus and more particularly relates to a novel magnetic structure controlling the closing and opening operation of a circuit breaker.

In recent years, the rapid expansion of mercury arc rectifier installations at 600 volts, D. C., both as to the total kw. installed and the relatively large number of units operated in parallel, has emphasized the importance of switchgear in providing suitable rectifier operation. In the event of a backfire, the rates of current rise through a rectifier and its transformer windings lie, in general, between three million and six million amperes per second. With large installations, where 60 units of 5000 amperes each are operated in parallel, the ceiling value of these currents is far above a figure which could be tolerated both from the standpoint of continuity of operation and safety to equipment.

High speed breakers having a time of approximately .5 cycle from backfire initiation to current limitation may permit, in some installations, peak currents in the neighborhood of 60,000 amperes. While such a value is appreciably below that which would cause equipment damage, it is nevertheless undesirably high, in that surges and "sympathetic" backfires on other units often result. Breaker duty and maintenance are higher than would be the case with lower values of backfire current and the factor of safety is not as great as is desirable.

Application Serial No. 371,092, filed December 21, 1940, now Patent No. 2,390,966, issued December 11, 1945, shows in Figure 15 the current path during a backfire in a six phase rectifier. It will be noted that the current flowing through the cathode breaker is supplied by other rectifiers on the bus, and that the current flowing through the anode breaker is the same current plus the additional current from the other anodes of the faulted rectifier.

Under these circumstances high speed breakers are essential to insure effective interruptions.

The speed with which the armature of the trip or opening magnet functions is a material factor in the time of circuit breaker operation. Obviously, the lighter the mass of the armature, the less its inertia and the faster it can operate. On the other hand, the armature must have a sufficiently large effective area.

The breaker of the present invention employs a magnet and armature design reducing the armature weight in a ratio of approximately 1:3, as contrasted with a conventional holding magnet.

2

As will be obvious, in order to secure the same effective armature area for a smaller weight of armature, I may decrease the radius and correspondingly increase the length of the armature.

Quite obviously, however, an armature of such great length compared to its diameter would be entirely impractical from a mechanical and stiffness point of view.

In accordance with my invention, I carry out this principle of weight reduction which overcomes the mechanical defects noted above.

I have discovered that I may materially reduce the mass of the armature and thereby increase the acceleration thereof by so arranging the magnetic structure of the holding magnet that there are, in effect, a plurality of individual magnets, each with its individual armature.

Inasmuch as the center of the armature which is mechanically connected to the movable contact of the circuit breaker assumes the greatest share of the carrying load in operating the movable contact and this load on the armature is gradually reduced as the edges of the armature are approached, I provide maximum thickness of metal at the center of the armature with a tapering armature construction toward the ends to a substantially reduced thickness at the ends.

This serves to prevent any deflection of the center of the armature which might tend to occur if the armature were of uniform cross-section; such deflection at the center should it occur would result in a reduction of the holding force on the armature and hence result in a rapid progressive release of the armature.

In order that the distribution of armature mass in this manner from maximum thickness at the center to minimum thickness at the ends may correspond to the flux distribution, the magnetic circuits are so arranged that a maximum number of lines of force exist at the center and the number of lines of force is reduced towards the edges of the armature.

My novel circuit breaker provides for tripping of the breaker on de-energization of the holding magnet armature and permits the armature of the magnet to be operated into engagement with the pole face of the magnet while the circuit breaker is still in disengaged position, the actual closing operations of the circuit breaker being performed by a separate power supply.

Accordingly, an object of my invention is to provide a novel magnet having a plurality of magnetic paths, each for conducting individual fluxes flowing through individual portions of the armature.

A further object of my invention is to provide a novel armature structure in which the portion of the armature subject to the greatest load carries more lines of force than other portions of the armature which carry smaller portions of the load.

Still another object of my invention is to provide a novel armature, the mass of which has been reduced to a minimum for the load it carries.

Still another object of my invention is to provide a novel magnet having novel magnetic path structures.

Still a further object of my invention is to provide a novel construction of a holding magnet in which tripping is effected by de-energization of the magnet armature.

Still a further object of my invention is to provide a novel circuit breaker structure in which a flexible connection extends from the armature to the movable circuit breaker contact.

There are other objects of my invention which together with the foregoing will appear in the detailed description which is to follow, in connection with the drawings, in which:

Figure 1 is a schematic view of my circuit breaker operating element showing the contacts closed.

Figure 2 illustrates the open position of the circuit breaker in Figure 1.

Figure 3 is a view corresponding to that of Figure 1 showing the movement of the apparatus for normally opening the circuit breaker.

Figure 4 is a diagrammatic showing of a slightly modified form of circuit breakers wherein a solenoid closing mechanism is utilized instead of a motor.

Figure 5 shows the circuit breaker of Figure 4 in closed position.

Figure 6 is a detailed showing of a portion of the apparatus of Figures 4 and 5.

Figure 7 is an exploded view in perspective of the operating magnet of my circuit breaker.

Figure 8 is a view in perspective of my operating magnet in assembled position.

Figure 9 is a cross-sectional view taken on line 9—9 of Figure 8.

Figures 10 and 11 are diagrammatic views illustrating the operations of the magnet of Figures 7 and 8.

Figures 12, 13 and 14 are additional diagrammatic views further illustrating the operation of the magnet.

Figure 15 is a diagram of a composite current oscillogram comparing $\frac{1}{2}$ cycle and $\frac{1}{4}$ cycle anode circuit breakers employed in my invention.

Figure 16 shows the arcing structure.

Referring now to Figures 1, 2 and 3, I have here shown in schematic form the construction and operation of a circuit breaker utilizing my invention. The circuit breaker here shown includes circuit connecting members 11 and 12, which form the terminals of the circuit breaker and are arranged to be connected into the external circuit.

An L-shaped stationary contact member 13 having a contact surface 14 and a securing bracket 15, is mounted by means of the bolt 16 on the connecting bar 11. The stationary contact 13 may be engaged by the movable contact 17 which also is an L-shaped member having a contacting surface 18 and a mounting bracket 19. A bolt 20 passes through the mounting bracket 19 and secures the movable contact 17 to the upper portion of the movable contact carrying lever 22.

Lever 22 is pivoted for rotational movement at 23. A flexible laminated conductor 24 is secured in any suitable manner, as for instance, by the bolt 25 to the lower end of the lever 22, and at its opposite end is secured by the bolt 26 to the end of the connecting bar 12.

When, therefore, the circuit breaker contacts are closed a circuit is completed from conductor 11 through the stationary contact 13 to the movable contact 17 through the movable contact carrying lever 22 and the flexible lead 24 to the connecting bar 12. A tension spring 30 is connected at one end to the ear 31 on the movable contact carrying lever 22, and at the other end, the spring 30 is connected to a lug 32 mounted on the frame of the mechanism. Tension spring 30 therefore biases the movable contact carrying lever 22 into counterclockwise rotation and hence biases this member to open circuit position.

When the circuit breaker is open as seen in Figures 2 and 3, then the movable contact lever 22 rotates counterclockwise against the stop 36, which limits further rotational movement thereof. The said stop is, of course, arranged in such position as to permit the movable contact to move a sufficient distance away from the stationary contact to ensure proper circuit interrupting capacity.

When closed, the contacts are normally maintained in engagement by means of the flexible member 35, which may take any desired form, such as a chain. The chain 35 is connected at one end to an ear 36 mounted on the contact lever 22 preferably approximately midway between the pivot point 23 and the free end which carries the movable contact 17. This chain passes over the roller 37 which is mounted on the operating crank 38. The other end of the chain is at 39 secured to the armature 40 which is normally held in engagement with the operating magnet 42.

The armature 40 is pivotally mounted on the lever 44 which is rotatably mounted on the pivot 45, which in turn is carried by lugs 46 associated with the frame of the magnet 42.

The magnet 42 is normally energized by a constant potential direct current coil 47 which provides adequate flux to maintain the armature 40 in contact with the pole pieces against the pull of the spring 30 transmitted by the chain or flexible member 35.

Current flowing through the series conductor 12 affects the flux between the magnet and the armature so that under certain conditions of direction and intensity of current flow, as hereinafter described, the flux through the armature is inadequate to counteract the effect of the spring 30, and the circuit breaker contact is pulled to open position.

The crank 38 may be operated for the purposes hereinafter described to close or to open the circuit breaker independently of the magnet 42 and the armature 40.

A motor 50 is used to operate a multi-pole unit, driving, through an insulating shaft, the high speed shaft 51 of small speed reducers 52; one speed reducer being mounted on each pole. The low speed shaft 53 of each speed reducer carries the crank 38 and its roller 37.

If the motor 50 is run sufficiently to drive crank 38 through 360° and the armature 40 is sealed against the pole face of magnet 42, the effects of the chain 35 riding on the crank roller 37 is to cause the breaker to go through an open-close cycle, as shown in Figures 1 and 3.

A limit switch may be utilized for controlling the motor which, with suitable braking, ensures that the crank and roller will stop at the proper point in the operating cycle either for closing or opening.

In Figure 2, the circuit breaker contacts are shown in the open position, having opened automatically because the flux in the magnetic path of magnet 42 and the armature 40 was reduced beyond the critical value necessary to counterbalance the opening force exerted by the spring 30.

Accordingly, the spring 30 has caused the lever 22 to rotate counterclockwise, thus pulling the chain 35 over the roller 37 and lifting the armature 40 away from its magnet 42.

Figure 3 shows the first necessary step for reclosing the circuit breaker after it has opened to the position shown in Figure 2. With the breaker contacts disengaged and armature 40 in its uppermost position, the crank 38 is rotated by motor 50 through 180° so that the armature is permitted to fall by gravity against the pole face of magnet 42, and the flexible member 35 is shown completely slackened having no tension at this particular phase of the operation. The circuit breaker may now be reclosed by energizing the coil 47 to assure that there is adequate holding flux passing through the armature 40. The shaft 53 is then rotated by means of the motor preferably in a clockwise direction to rotate the crank 38 and the roller 37 so that flexible member 35 is drawn taut and then is effective to pull the contacts into engagement and maintain them in the position shown in Figure 1.

To open the circuit breaker without relying on the automatic circuit breaker opening means, the field coil 41 may be deenergized, which will result in the release of armature 40 and a consequent opening of the circuit breaker; or the motor 50 may be rotated so that shaft 53 is rotated through 180°, thus bringing the circuit breaker to the position shown in Figure 3. In each case, the circuit breaker may be opened.

In the foregoing, the principle of the formation of my circuit breaker has been set forth in its simplest form.

Either of the contacts 13 or 17 may obviously be resiliently mounted upon their respective supports.

The type of holding magnet shown in Figures 1, 2 and 3, is of a conventional "bucking bar" type well known in the art. The actuating mechanism of the circuit breaker may, of course, be effective with any of the well-known releasable holding means. The type of holding magnet which I prefer, however, to use in the circuit breaker of the present type, and which also has many additional functions and operations, is that shown in Figures 4 to 14 inclusive.

However, in Figures 4, 5, and 6, I have shown a somewhat modified type of circuit breaker which may operate in the same general manner, and which may be described in its simplest terms before the exact operation of the magnet itself is set forth.

In Figure 4, the modified circuit breaker is shown having the holding magnet 80 of my invention which is energized by the field coil 61, which may create sufficient flux to attract and hold the armature 62. The field coil 61 may be energized from any direct current source as 88, the circuit to the field coil being closed by, for instance, the switch 64. The armature 62 is pivotally mounted on the lever 67 which, in turn, is pivoted at 78 on the member 80, which is rigidly attached

to the frame of the magnet 80. The opposite end of the lever 67 may be slotted, or, as is shown in the figures, bifurcated at 71 to receive the rod extension 72 of the solenoid plunger 73 normally held in the position shown by compression spring 80'. The rod 72 is arranged for engagement with the upper surface of the lever 67 by means of the button 75 which is secured to the upper portion of the rod 72.

10 The contact members in the present case are illustrated as bridging contact 76, which, in the open position of the circuit breaker, bridge the contact members 71, 77 and, in the closed position of the circuit breaker, bridge the contact members 78, 79. The members 78, 79 are, of course, the main current conductors, while the members 71, 77 may, when bridged, energize any appropriate relay or signalling apparatus, or any appropriate motor circuit or other apparatus necessary for effective operation of the circuit breaker when it is open.

In order to close the circuit breaker, that is, in order to move the armature 62 from the position shown in Figure 4 to the position shown in Figure 5 so that the bridging contact member 75 may bridge the contacts 78, 79, the field coil 61 is first energized by closing the circuit thereto through the switch 64. Thereafter, the solenoid coil 80 is energized by closing the switch 82, thus connecting the current source 88 through the leads 83 and 85 to the coil 80. The plunger 73 is attracted downwardly thus pulling the rod 72 downwardly and engaging the button 75 with the upper surface of the lever 67, and pulling the lever 67 downwardly.

The armature 62 is normally urged into raised position by the tension spring 87 fixed at its upper end and engaged at its lower end to the upper portion of the rod 88 which, in turn, is secured to the armature 62. The attraction of the solenoid plunger 73 downwardly by the coil 80 pulls the lever 67 and the armature 62 downwardly against the force of the tension spring 87. When the downward movement has been completed, and the armature 62 has been sealed against the pole faces of the magnet 80, the circuit breaker will normally stay closed despite the fact that the switch 82 (which may be a spring operated switch biased toward open position) now opens. That is, as long as the magnetic flux of operating magnet 80 through the armature 62 is sufficient to counteract the force of the spring 87, the circuit breaker will remain closed, and the contacts 78, 79 will be bridged.

55 Accordingly, the solenoid plunger 72 may be permitted to return again to the raised position under the bias of, for instance, a spring mounted directly beneath it.

In Figure 6, I have shown the position of the solenoid plunger and the rod 72 with respect to the lever 67 at the moment the closing operation has been completed and before the solenoid plunger has been permitted to rise again to the position shown in Figure 5.

When, now, owing to current conditions, hereinafter described, which cause a decrease in the holding flux exerted by the magnet 80 through the armature 62, the holding force of the magnet decreases below the pull exerted by the spring 87, the spring 87 is free to pull the armature 62 upwardly and, consequently, remove the bridging member 76 from bridging engagement with the contact 78 and to bridge the contact member 77, 79. The holding or operating magnet 80 and its

function is set forth in Figures 7 to 14 inclusive and constitutes a vital element of my invention.

Referring now to Figure 7, there is here shown in partially exploded form the holding magnet 60 which constitutes a primary element of my invention. The holding magnet, as may be seen in Figure 7, comprises a rectangular structure consisting of stacks of laminations which provide spaced and interleaved pole pieces of opposite polarity. This system provides a plurality of short flux paths (hereinafter described in connection with Figure 12) through the armature and results in an extremely quick acting release. The electrical and magnetic properties and the advantages in actual operation of my holding magnet will be more specifically set forth after the following description of the specific physical arrangement thereof.

The stacks of laminations are held together by a pair of non-magnetic frame plates 101 and 102. Plate 101 is provided with a plurality of tapped perforations 103, 103 to receive the ends 104, 104 of a plurality of studs 105. Studs 105 are insulated from the metallic laminations hereinafter set forth by the insulating bushings 106, 106. These studs 105 pass through corresponding openings 108, 108 in each of the metallic laminations as hereinafter set forth, and also pass through openings in the lower plate 102—all of the openings in the plates and in the laminations being in registry with each other. The lower end of the studs are also threaded, and the entire assembly is securely integrated as a single unit by means of the nuts 111 which are threaded onto the ends 110 of the studs 105, and held in place by the lock washers 111a and washers 111b. The washer 111b is of insulating material to ensure that the nuts 111 are appropriately insulated from the plate 102.

A central opening 115 is provided in each of the plates 101 and 102 and registers with corresponding openings in each of the laminations formed by the plurality of magnetic sheets, as hereinafter set forth, in order to form a central opening through the entire structure through which the conducting bar 12 passes.

In Figure 7, the plate 101 and one layer of laminations and its associated insulating spacing plate is shown lifted from the entire stack in order better to illustrate the complete unit.

In the construction shown in Figure 7, the holding magnet is provided with five layers of laminations 121 to 125. Each of these layers of laminations is separated from the adjacent layer by insulating plates 126 to 129 respectively.

Referring now to layer 121, this layer, as do each of the others, consists of two sets of laminations. One of the sets or stacks 132 comprises sheets which are L-shaped in formation with one limb 133 forming the sides of the structure and provided with openings 108, 108 to receive the studs 105. The other limb 135 forms a magnetic pole in the manner hereinafter described.

Layer 121 comprises, in the same plane with laminations 132, another stack or layer of laminations 140 which consists of a plurality of sheets of a simple rectangular form and which forms an element of the other side of the structure. The stack 140 is also provided with openings 108, 108 to receive the insulated bolts. An air gap 142 is provided between the limbs 135, forming a pole piece, and the end of the rectangular stack of laminations 140. The insulating plate 126 is placed immediately beneath the layer 121 and immediately above the layer 122 in surface

to surface engagement on opposite sides with each of the layers.

While sheet 126 should preferably be an insulating non-metallic sheet, it is sufficient, however, for purposes of operation of the holding magnet that it merely be a non-magnetic member. The insulating sheet 126 is U-shaped in formation and is provided with the central opening 115a which registers substantially with the central opening 115 in each of the outer plates 102 and 101 to permit the conducting bar 12 to pass therethrough. Sheet 126 also has openings 106, 106 to permit the insulating bushings to pass therethrough.

The next group of laminations immediately beneath, that is, layer 122 has the same form as the laminations in layer 121, but the members are reversed with respect to each other. Thus, the stack 140a in layer 122 extends immediately beneath the limb 133 of stack 132 in layer 121; and limb 133a of stacks 132a in layer 122 extends immediately beneath the stack 140 in layer 121.

In layer 123, the positions of the stacks are again reversed so that the L-shaped stack extends beneath the L-shaped stack of layer 121, and the rectangular stack of layer 123 extends beneath the rectangular stack in layer 121.

In layer 124, the positions are again reversed so that the arrangement of the stack corresponds exactly to that of layer 122; and again in layer 125, the positions are reversed so that the arrangement of the stacks in the layer corresponds to the arrangement in stacks 123 and 121.

Thus, in each adjacent layer, an L-shaped stack is in alignment with a rectangular stack, and a rectangular stack on the opposite side is correspondingly in alignment with the adjacent L-shaped stack on either side of the layer.

Insulating spacing plates 127, 128 and 129, similar in every respect to spacing plate 126, are introduced between successive layers of laminated stacks so that each successive laminated layer 121—125 is magnetically isolated from the others.

The laminated stacks, as well understood, are formed of magnetic material so that appropriate magnetic fluxes may be created in accordance with the operating characteristics hereinafter set forth.

An air gap 142 is provided in each layer between the rectangular stacks and the adjacent limb 135 of the L-shaped stack in the same layer for purposes hereinafter described in connection with Figure 14.

The pole pieces are formed by the limbs 135, 135a, 135b, 135c and 135d in the stack. Adjacent poles in adjacent layers are of opposite polarity in accordance with the structures hereinafter described. Thus, should pole 135 be north, then pole 135a will be south, 135b will be north, 135c south, and 135d north. The poles of opposite polarity are interleaved as shown in Figure 7 so that they extend substantially between each other to provide proper terminals for the magnetic paths through the armature in the manner hereinafter described. The manner in which the poles become of opposite polarity should be obvious upon inspection of Figure 7. Thus pole face 135 extends from the right-hand end 132 of the structure, and current induced in the laminated stack will produce a magnetic flux of a specific direction therein.

In layer 122, the fluxes will be of the same direction, but, however, pole face 135a extends

from the left-hand side of the stack, and hence this pole will be of a polarity opposite to that of pole 135. Similarly, pole 135b extends once more from the right-hand end of the stack and pole 135c from the left-hand end so that in each case the polarity will be opposite. The arrangement is followed throughout the stack so that adjacent interleaved poles are of opposite polarity.

In order to complete the magnetic circuit between the ends of the laminations remote from the pole pieces, a single stack of rectangular laminations 150 is provided. This stack of laminations is secured between the end frame members 101 and 102 in spaced relation to the ends of the other laminations so that an air gap 151 is provided between the ends of stacks 132 and 140 and the stacks 150. This is done in order to reduce the possibility of saturating the magnetic material during normal operation.

The stack 150 is maintained in position, as will be obvious in Figure 7, by the insulated studs 105 which pass through corresponding registering openings in the stacks and in the end frame members.

The specific manner in which the studs 105 and their insulating bushings pass through the stacks of laminations and the end frames is shown in the cross-sectional view of Figure 9 where the stud and bushing passing through the registering perforations of the stacks 135 and 140 are shown. From Figure 9, it may readily be seen that the studs 105 do not provide any conductive path between the stacks. Preferably, the stud 105, while they may be of metal, should be of non-magnetic material so that undesirable flux paths will not be provided.

In the assembly operation, the studs 105 are threaded into the threaded openings 103 in the frame member 101. The insulating bushing 106 is then placed thereover, and the successive stacks of laminations and their respective insulating spacers are then placed over the studs, and the entire assembly locked in place by the nuts 111 and their associated members.

When the various laminations and their insulating spacers and insulating frames are united in a single unit, they then assume the form shown in Figure 8.

The series conductor or bus bar 12 is shown passing through the opening 115 in the entire magnetic structure. The armature 40 is shown resting against the pole faces; and the direct current energization for the magnetic structure is provided by the coil 61, the action of which corresponds to the action of coil 61 in Figure 4 or the action of coil 47 in Figure 1.

This direct current energization of the magnetic structure is obtained by reason of a magnetic interconnection between the coils and the magnetic structure. For this purpose, solid iron pole pieces 160, 161 are provided—these members being secured against the sides of the magnetic laminations by bolts 163 which pass through openings in the pole pieces 160 and 161 and enter the tapped perforations 164, 164 in the sides of the frame members 101 and 102 (see Figure 7).

A bolt 167 passes through perforations in the opposite pole pieces 160 and 161 (Figure 8), and maintains the magnetic core in position between these two pole pieces. This magnetic core corresponds to the member 167' of Figures 4, 5, 10 and 11. Although the poles 160 and 161 are shown extending to the right of the laminations 135 and 140 in Figure 10, they may be reversed in direction if desired as shown in Figure 11. The coil

61 with terminal connection 168 (Figures 4, 5, 10 and 11) provides proper energization.

The direction and intensity of the magnetic flux of the magnetic structure herein described is influenced by two factors:

The first factor is the direction of the current flowing in the bus bar 12 which passes through the central opening 115 in the magnetic structure. This flux, however, is not relied upon to generate any holding force.

The other component of the magnetic flux in the magnetic structure is created by the pole pieces 160 and 161 and their core 167', which is surrounded by the coil 61.

The direct current energization of the coil 61 produces a magnetic flux in the core 167' and in the pole pieces 160 and 161 through the poles 135 and 140 in each layer of the stack.

These composite actions are shown more specifically in Figure 10.

Thus in Figure 10 when the coil 61 is energized by a direct current source in a desired direction, the magnetic fluxes in the structure are shown by the arrows. The direct current coil 61 creates a magneto-motive force driving the flux through the poles 160 and 161 to the edges of the stacks of laminations.

This flux in the schematic showing of Figures 10 and 11 will flow through pole 161 through one of the magnetic laminations 135 and then through the armature 40 to the adjacent opposite pole 135a, returning through pole piece 160. A parallel magnetic circuit is provided from pole piece 161 through laminations 135b, armature 40 to laminations 135a, returning through pole piece 160. The flux flowing in laminations 135b divides as shown in Figure 12, some flowing through the armature 40 to laminations 135c and pole piece 160.

The manner in which the flux flows from pole to pole through the armature in each case is shown in the schematic cross-sectional view of Figure 12.

Thus, the flux in the laminations is divided into a plurality of parallel flux paths through the armature, each of the paths including only its individual portion of the armature as distinguished from prior magnet structures in which all of the flux in the magnetic structure must flow through the entire armature. Accordingly, for the same armature mass, my present structure will conduct a considerably larger number of flux lines by reason of the number of multiple magnetic paths than is the case of the standard magnet in which all the flux flows through the entire structure in a single series path.

In addition to the flux paths between 135, 135a—135d as will now be apparent, flux paths are provided from lamination 135 through armature 40 to laminations 140, 135a to 140a, etc. These paths are provided by reason of the slight overlaps of the armature 40 as shown in Figure 10 which magnetically connects laminations 135 with 140 through armature 40 and similarly magnetically connects each of the other corresponding sets of laminations.

Consequently, the magnetic flux flows not only from pole 135 through the stack 140 in each layer, but also flows from pole 135 to pole 135 in successive layers—the armature 40 providing the magnetic path between successive poles in successive layers. The flux thus provided is sufficient to maintain the armature 40 against the pole pieces, against the bias of the spring 87 or 88.

When current is flowing in the normal direction in the bus bar 12, as shown in Figure 10, it creates a flux through the magnetic structure, in the direction indicated by the arrows, which augments that created by the current in the coil 61, so that the armature is even more firmly secured in position.

As may now be seen in Figure 11, should the direction of the current in the bus bar 12 be reversed, a flux through the magnetic structure in the reverse direction will be created thus tending to counteract the effect of the flux created by the coil 61. These two fluxes opposing each other thus will reduce the flux passing through the armature to a point where the bias of the spring 80 or 87 will be sufficient to overcome the pull of the magnetic structure, and the armature will be released to permit the circuit breaker contact to separate.

While in Figures 8, 10, and 11, the magnetic circuit of the shunt coil 61 is shown as not embracing the bus bar 12, it might be advisable under certain desired conditions to extend the pole pieces 160 and 161 so that the magnetic flux in these members will also embrace the bus bar 12. A reversed current in the bus bar 12 will then not merely create a reversal of the magnetic flux in the magnetic structure itself, but will also set up a magneto motive force in the pole pieces 160 and 161 in a direction opposite to the magneto-motive force exerted by the coil 61, thus tending further to diminish the net magnetic flux tending to maintain the armature in position and permitting an even quicker release of the armature 40.

It will thus be seen from an examination of Figures 10 and 11 that the magnetic structure and its energizing coil 61 and the magnetic force exerted thereby is sufficient to hold the armature 40 in position, and that this holding force is accentuated when current is flowing through the bus bar 12 in the forward direction.

When current flows in the bus bar 12 in a direction opposite due to a fault condition, this magneto motive force is counteracted, as shown in Figure 11, and is rapidly diminished to an extent where the armature 40 may be released.

By reason of a plurality of poles which are thus provided, I have found that a very small armature, weighing approximately of the order of .55 pound, is all that is needed to maintain closed contact position of the circuit breaker. The weight of the armature may thus materially be reduced. The inertia of the parts, which must be brought into motion upon the occurrence of a condition which makes it necessary that the circuit breaker open, is also greatly reduced and the opening time of the circuit breaker is correspondingly decreased. The armature need only be sufficient to provide an appropriate path for the magnetic fluxes, as shown in Figure 12, and need only be physically strong enough to support the chain or flexible member 35 which is secured at 38 to the armature.

In Figure 12, I have shown a cross-section through the magnetic pole pieces and the armature along approximately the center line. Again, since the armature need only be of sufficient thickness and strength to carry the flux between adjacent pole pieces, and thus is, in effect, a plurality of small armatures bridging separate air gaps, the cross section of the armature may become so small in respect to the physical force existing that in an armature of uniform cross section, an effect may very well be created where-

in the center of the armature may be deflected. That is, the point 39, at which the external force exerted by the flexible chain 35 is exerted, may be drawn away from the pole face owing to the relatively small cross section required for the armature. In such a case, the slight flexing of the armature, which permits the center area thereof to be drawn away, may thus decrease the magnetic flux therethrough at the center. This decrease in magnetic flux at the center will thus decrease the net counteracting force exerted by the magnetic structure to the pull at the point 39, thus permitting the pull to be exerted more strongly, thus making it possible for the center of the armature to be deflected even more, and thereby permitting a greater portion of the armature to be drawn away. This successive action, which may occur very quickly, will, owing to the flexing of the armature, permit the armature to be released.

Accordingly, the armature 40 is thickened at its center portion to provide a better path for the passage of magnetic fluxes thereat, and the center stack of laminations is thickened so that the center pole face 185b is much thicker than the other pole faces.

Similarly, the pole faces adjacent the center pole face, that is, pole faces 185a and 185c, while not as thick as pole face 185b, are much thicker than pole faces 185 and 185d.

Since the stacks of laminations toward the center of the magnetic structure have the greatest thickness, consequently, they also have the greatest pole area and provide the largest amount of flux flowing into the armature. The armature itself, since it is thickened at the center, also provides an appropriate path for this increased amount of flux. This flux is progressively decreased toward the center of the armature.

It thus becomes possible to provide an armature of a minimum weight with greater physical strength than in cases where an armature structure of uniform cross-section throughout is used.

Thus, in Figure 12, the poles 185, 185b and 185d and indicated as being north. Flux lines 200 flow from pole 185 into the intermediate pole 185a. Also, flux lines 201 flow from pole 185d into the intermediate pole 185c. Flux lines 202 and 203 flow from the central pole 185b into the intermediate poles 185a and 185c. In each case, the magnetic circuit is completed from pole to pole through the pole pieces 160 and 161 through the core 161'.

On the occurrence of reverse current conditions in the bus bar 12, as shown in the diagrammatic sketch of Figure 11, the flux tending to hold armature 40 in place against the force of the counteracting spring is reduced so that the armature is permitted to move away from the magnetic structure. As armature 40 moves a slight distance away from the magnetic structure, as shown in Figure 13, thus creating the air gap 210, then, under normal or steady current conditions, the introduction of such an air gap will cause the building up of the leakage between the adjacent poles so that the flux passing into the armature is so rapidly reduced that the pull exerted by the magnetic structure becomes substantially zero at a very small air gap 210, and the armature may then be drawn away from the magnetic structure very quickly.

During practical operating conditions in some installations, a fault current may increase in value at an exceedingly high rate. There are

installations in which the rate of rise in current may be increased at ten million amperes per second. Under such conditions, it is essential that the speed of movement of the armature and the rate of rise of the flux in the air gap be so arranged that there shall be no tendency for the armature to be drawn back against the pole piece and so prevent the opening of the circuit breaker.

While the condition shown in Figure 13 represents a leakage flux from one pole piece to an adjacent one, which will occur during normal operating conditions, high rate of rise may change this action. At a very high rate of current rise, the flux increases correspondingly. I have found that rapidly changing flux will flow normally parallel to the plane of the laminations, and that they are so guided by the outer laminations that the cross leakage is substantially zero. Any flow of this flux of rapidly changing value normal to the plane of the laminations would tend to create eddy currents which would tend to oppose the cross flow. As a result of this condition, the situation shown in Figure 13, would not exist during a fault involving a very high rate of rise in current, and for this reason, it is necessary to provide, as shown in Figure 14, a relatively narrow air gap between the ends of a pole 135 and the rectangular stack 140. This air gap will provide a leakage for the flux produced by a current changing any value of rate of rise so that the tendency to draw the armature back against the pole pieces is eliminated.

From the above, it will now be clear that the magnetic path for fluxes flowing through the pole piece 160 is distributed through the laminations 124 to 125. Because of the variation in the number of laminations in section 121 as compared to the next section 122 and 123, less lines of force will flow in the laminations 121, a greater amount of flow in 122 and still a greater amount in 123. The lines of force flowing in laminations 135 of layer 121 will in turn divide themselves, a larger proportion of such fluxes flowing from the lamination 135 to lamination 135a through the portion of the armature bridging 135 and 135a as shown at 200 in Figure 12.

A smaller proportion of such fluxes flows from lamination 135 through the armature which bridges the gap 142 to the layer 140. This is due to the fact that the reluctance of the smaller path to the armature from layer 135 to 140 is greater than the reluctance of the much larger path provided by the armature from layer 135 to 135a.

Moreover, the lines of force flowing in the magnetic structure are greater than the lines of force which could be carried by the armature cross-section at this point which further determines the distribution of lines of force.

In general, the distribution of magnetic lines of force is as illustrated in Figure 12. A relatively small number of lines flows from lamination 135 to 135a through the armature of reduced cross-section. A much larger number of lines 202 flows through laminations 135a and 135b through the armature of greater cross-section at this point. Thus, the portion of the armature which is subjected to greatest load also has the greatest mass of material and carries the largest number of lines of force and the portion of the armature which carries the least load is of the least cross-section and carries the minimum number of lines of force.

In order to further reduce the mass of the armature, a V-shaped groove is cut therein as shown at 171 in Figure 8, since the magnetic paths are such that substantially no lines of force would be flowing through this portion of the metal.

This is better shown and more evident from an examination of Figure 12, which shows portions of the metal between the lines of force 202 and 203 which perform no useful function in carrying magnetic lines of force.

This same principle may be carried out in other portions of the armature, if desired.

The blow-out structure which I have found 15 operating satisfactorily with the present circuit breaker is shown in Figure 16.

With the previous breaker, the current reached a value under a certain set of test conditions of 30,000 or 35,000 amperes when arcing was initiated, whereas, with this higher speed breaker, arcing may be initiated at appreciably less than half this value. As a consequence, satisfactory speed of arc travel during the early formation of the arc with the prior arc extinguisher was unsatisfactory, resulting in distress and delayed current limitation.

The structure of Figure 16 employs a strengthened primary blowout responsible for initial arc motion and the transfer to the secondary blow-out is made much earlier.

While I have here described my invention in connection with preferred, successful embodiment thereof, many variations in the actual form of the interleaved pole pieces, and many variations in the form and construction of the armature and of the circuit breaker itself, as well as many variations in the "bucking bar" arrangement and in the exciting coil and other elements of my invention, will now be obvious to those skilled in the art. Accordingly, I prefer to be bound not by the specific disclosures herein but only by the appended claims.

I claim:

1. In a holding magnet, a plurality of magnetic conductors of one polarity a common magnetic path for all of said magnetic conductors; a plurality of magnetic conductors of an opposite polarity; said magnetic conductors being arranged in a stack parallel to each other, the magnetic conductors of one polarity being interleaved between the magnetic conductors of the opposite polarity and spaced from each other; and an armature having a face simultaneously engageable with each of said magnetic conductors and completing a plurality of magnetic paths between adjacent magnetic conductors, the adjacent magnetic conductors providing leakage paths between each other when said armature moves away from said conductors.

2. In a holding magnet, a plurality of magnetic conductors of one polarity a common magnetic path for all of said magnetic conductors; a plurality of magnetic conductors of an opposite polarity; said magnetic conductors being arranged in a stack parallel to each other, the magnetic conductors of one polarity being interleaved between the magnetic conductors of the opposite polarity and spaced from each other; and an armature having a face simultaneously engageable with each of said magnetic conductors and completing a plurality of magnetic paths between adjacent magnetic conductors; said magnetic conductors having a different cross-sectional area; the cross-sectional area of the armature opposite 70 each magnetic conductor being correspondingly

different, thicker portions of the armature registering with thicker magnetic conductors.

3. In an electromagnet, a magnetic structure comprising a pair of pole pieces, an armature operable to an energized and de-energized position, means for providing a closed magnetic path through said magnetic structure and said armature and for providing a magnetic path bypassing said armature, the magnetic path through said armature when said armature is in its energized position providing a lower reluctance magnetic path than said by-pass and said armature as soon as said armature starts to move to its second position providing a greater reluctance magnetic path than said by-pass.

4. In an electromagnet, a magnetic structure comprising a pair of pole pieces, an armature, a plurality of magnetic conductors extending from each of said pole pieces, said armature being in physical contact with said conductors when said magnet is energized and completing a magnetic circuit from one of said magnetic conductors extending from one of said pole pieces to one of said magnetic conductors extending from the other of said pole pieces, one of said magnetic conductors from one of said pole pieces being closely positioned to the end of said armature, means for providing a magnetic path completing said first mentioned magnetic path and presenting a large surface area to one of said magnetic conductors extending from the other of said pole pieces and spaced therefrom to produce a high reluctance by-pass magnetic connection relative to said armature path, said armature immediately on its first disengaging movement away from said conductors providing a greater reluctance magnetic path than said magnetic path by-passing said armature.

5. In an electromagnet, a magnetic structure comprising a pair of pole pieces, an armature, a magnetic conductor extending from each of said pole pieces and means for providing a magnetic path from one to the other of said pole pieces by-passing said armature, said armature engaging said conductors to provide a closed magnetic path to said pole pieces of less reluctance than said by-pass and said armature introducing an air gap connection in the magnetic path including said armature having a greater reluctance than said by-pass as soon as said armature breaks the contact connection to said magnetic path.

6. In an electromagnet, a magnetic structure comprising a plurality of pole pieces, an armature, a magnetic path through said pole pieces and said armature, and a magnetic path through said pole pieces and by-passing said armature, said armature presenting a closed iron magnetic circuit of less reluctance than said by-pass when said electromagnet is energized and said armature presenting an air gap connection in its magnetic path having a greater reluctance than said by-pass as soon as said armature moves on de-energization of said electromagnet.

7. In an electromagnet, a laminated magnetic structure, an armature having an energized and a de-energized position, means for providing a magnetic path through said magnetic structure and said armature, and means for providing a magnetic path by-passing said armature, the magnetic path through said armature when said armature is in one of its positions providing a lower reluctance magnetic path than said by-pass and said armature as soon as it starts to move to its second position providing a greater reluctance magnetic path than said by-pass.

DONALD I. BOHN.
